Primary Examiner — Elizabeth J Oswecki(74) *Attorney, Agent, or Firm* — Clifford L. Tager(57) **CLAIM**

The ornamental design for tong heads, as shown and described.

DESCRIPTION

FIG. 1 is a front view of tong heads showing our new design; FIG. 2 is a top view thereof;

FIG. 3 is a right side view thereof, the left side view being a mirror image;

FIG. 4 is a back view thereof; and,

FIG. 5 is a bottom view thereof.

The broken lines shown in the drawings represent portions of the tong heads that form no part of the claimed design.
